[57] ABSTRACT

A shotgun includes an action spring assembly forwardly urging the action bar. The action spring assembly has a pair of coil springs arranged in a row and a shock absorbing member interposed between the coil springs. The shock absorbing member is constructed by two rings so assembled that they may buffer the force applied to one spring and transmit the buffered force to the other spring when the action bar is returned to its original position.

FIG. 1

FIG. 2

FIG. 3

FIG. 4

ACTION SPRING ASSEMBLY FOR FORWARDLY URGING THE ACTION BAR OF SHOTGUNS

BACKGROUND OF THE INVENTION

This invention relates to a shotgun and more particularly to an improvement of an action spring assembly of an action bar used in the shotgun.

A conventional shotgun or fire arm is provided with an action bar which is rearwards moved through a piston with propellant gases generated upon firing of the shotgun so as to bring the shotgun to a waiting condition. The action bar is then returned to its original position by a coil spring when the pressure of propellant gases is decreased. The returning of the action bar by the coil spring heretofore has been accompanied with a great shock force and sound.

SUMMARY OF THE INVENTION

Accordingly, an object of the present invention is to provide an action spring assembly which may return the action bar of the shotgun without a great shock force and sound.

BRIEF DESCRIPTION OF THE DRAWING

FIG. 1 is a perspective view of a shotgun including an action spring assembly according to an embodiment of the present invention;

FIG. 2 is a sectional view of the part of the shotgun shown in FIG. 1;

FIG. 3 is an enlarged sectional view of the buffer member of the spring assembly; and

FIG. 4 is a perspective expanded view of a pair of rings of the buffer member.

DETAILED DESCRIPTION OF THE INVENTION

There will now be described one embodiment of the present invention with reference to the accompanying drawings.

As shown in FIG. 1, a shotgun body 1 is of a conventional configuration having a barrel 2, receiver 3, and butt 4. From the receiver 3 there is extended a magazine tube 5 on which an action bar 6 is provided as shown in FIG. 2. The action bar 6 includes a short cylindrical section or forward part 7a slidably mounted around the magazine tube 5 and a pair of parallel bars or rearward parts 7b with one end fixed to the rear upper part of the cylinder 7a and the other end connected to a sliding member as described later. The front end of the cylinder 7a is securely connected to the rear end of a piston 8 slidably received in a cylinder 10, so that the action bar may be moved with the piston. The piston 8 may be moved, rearwards or in a direction of an arrow A, against an action spring assembly 11 with propellant gases which have been generated in the barrel 2 at firing of the shotgun and then introduced into the cylinder 10 through an inclined passage 9 formed in the wall of the barrel.

The action spring assembly 11 is mounted around the

periphery of the magazine tube, which comprises a pair of coil springs 12 and 13 having substantially the same length and diameter, and a buffer member 14 interposed between the coil springs and contacted with them. The forward end of one coil spring 12 abuts on the rear end of the short cylindrical section 7a and the rear end of the other coil spring 13 is fixed to the flange 5a, so that the action bar 6 is usually urged in a forward direction of an arrow B by the spring assembly.

10 The buffer member 14 is constructed of a pair of metal rings 15 and 16 with the same diameter. One ring 15 is formed with a transverse cut 15a in the part of its periphery thereby to elastically expand to have its diameter broadened. At one end portion of the ring 15 there is formed an inclined inner surface 15b. The other ring 16 has at the end portion an outer surface 16b inclined at the same angle as the inclined surface of said one ring 15 so that both inclined surfaces 15b and 16b may be slidably contacted with each other.

20 The rear end of the action bar is connected to the sliding member 17 which is received in the under part of a bolt 19 slidably mounted in a charging room 18 expanded from the base of the barrel 2 to the receiver 3. As a conventional manner, the sliding member 17 may be slid within a certain range in the bolt 19. The bolt 19 may cooperate with the action bar 6 through the sliding member 17 and slid to a direction of an arrow C with propellant gases at firing of the shotgun.

25 With the spring assembly constructed as described above, when the action bar which has been slid in a direction of an arrow A is moved in a direction of an arrow B to return its original position, the buffer member of the spring assembly may buffer the force applied to one coil spring and to transmit the buffered force to the other coil spring, so that the shock force and sound are effectively decreased.

30 What is claimed is:

1. In a spring assembly returning an action bar to its original position which has been moved in one direction by a piston, the improvement comprising a pair of coil springs arranged in a row and a shock absorbing member interposed between said coil springs to buffer the force applied to one spring and to transmit the buffered force to the other spring, said shock absorbing member having first and second rings arranged coaxially with the coil springs and contacted with each other, the first ring being able to be resiliently expanded in a radial direction when being pressed by the second ring.

45 2. The spring assembly according to claim 1 wherein the first ring has a traverse cut.

50 3. The spring assembly according to claim 2 wherein the inner surface of the first ring has a portion inclined at an angle on one side and the outer surface of the second ring has a portion inclined at the same angle as the inclined portion of the first ring to contact with the same.
